[57] CLAIM

The ornamental design for a bottle cap or similar article, substantially as shown.

DESCRIPTION

FIG. 1 is a perspective view of a bottle cap or similar article showing my new design in an open, dispensing position;

FIG. 2 is a top plan view thereof;

FIG. 3 is a front elevational view thereof;

FIG. 4 is an elevational view looking from the left of FIG. 3;

FIG. 5 is a rear elevational view; and

FIG. 6 is a top plan view in a closed position.

FIG. 1

FIG. 2

FIG. 3

FIG. 4

FIG. 5

FIG. 6
